ANDRÉS PETIT, OF HABANA, CUBA.

TLTING PLATFORM FOR SIDE-DUMPING CARS.

1,313,416.

Specification of Letters Patent. Patented Aug. 19, 1919.

Application filed August 20, 1917. Serial No. 187,251.

To all whom it may concern:

Be it known that I, ANDRÉS PETIT, a citizen of the Republic of Cuba, resident of Habana, Cuba, have invented certain new and useful Improvements in Tilting Platforms for Side-Dumping Cars, of which the following is a full, clear, and exact specification.

This invention relates to tilting platforms for side dumping cars and particularly to tilting platforms for side dumping cars upon the carriers to cane mills and its object is to provide a new construction of tilting platform for receiving and discharging the contents of the cars by lateral inclination, this construction affording the advantages of safety and rapidity in its operation.

Another object of the invention is to provide a new construction of operating mechanism for said platform, which is simple, efficient and safe, and requires but slight exertion on the part of the operator.

This invention is described with reference to the figures of the annexed drawings, in 25 which:

Figure 1 is an upper plan view of the tilting platform for side dumping cars, constructed according to this invention.

Fig. 2 is a rear elevation of said tilting 30 platform partially in section.

Fig. 3 discloses a side elevation showing the tilting platform in the set position.

Fig. 4 is a detail in vertical section of the cross piece connecting the motion means and 35 the lever of the tilting platform.

Fig. 5 is a detail in horizontal section of said connecting cross piece.

Fig. 6 is an elevational detail of one of 40 the platform bolsters engaging the respective bolster of the supporting base.

Fig. 7 is a detailed vertical transverse section of said bolster.

The device comprises a platform formed by a plurality of bolsters 2 consisting of 45 beams of I cross section connected at their ends by an I cross section beam 4 and by a channel shaped beam 5 respectively, the bolsters 2 presenting at the forward portion of their lower edge a curve of large radius. 50 Said platform rests upon a supporting base embedded in the ground alongside of the

excavation 6 wherein the carrier of the cane to the mill moves, and said base consists of a plurality of longitudinal beams 7 upon which are mounted a plurality of transverse beams 8 corresponding vertically with the bolsters 2, the spaces between each two transverse beams 8 being filled with concrete material 9, to the upper surface of which a concave shape is given, as shown in Fig. 2. 60 By virtue of the curved shape of the forward ends of the lower edges of bolsters 2, the platform can tilt upon the supporting base, and in order to prevent a sliding movement of the platform upon the supporting 65 base, a gearing is provided between the bolsters 2 of the platform and the transverse beams 8 of the supporting base by means of a plurality of teeth 10 projecting upwardly in a spaced manner from the top 70 of the transverse beam 8 and a plurality of notches 11 formed in a spaced manner in the lower curved edges of bolsters 2 of the platform, to which end a proper depth is given to said lower edge. On the bolsters 75 2 are track rails 12 upon which the loaded car is run. The pivotal center of the curved lower surfaces of the bolsters 2 lies in a plane midway between the track rails and the flat lower surfaces of said bolsters extend from said curved surfaces to a point 80 below the inner track rail.

To the side beam 4 of the platform there are connected by means of two triangular plates 14, two levers 15 angularly arranged, 85 and consisting of I beams, the connection being reinforced by means of auxiliary pieces 16 secured by means of plates 17 and the converging ends of the bodies of said levers 15 are bent so as to be connected by means 90 of bolts to the similarly united and bent ends of the branches of a fork 18 which consist of vertical plates connected at their end by a vertical plate 19 having angularly bent ends which are bolted within the branches 95 of said fork, each branch presenting a horizontally extended opening 20 for the purpose hereinafter disclosed.

The fork 18 remains in a cross relation to a vertical frame formed by three columns 100 21, 22 and 23 of I cross section and each buried in the ground at their lower end and

separated at a certain distance one from the other and connected at their upper ends by means of a cast bridge 24, so that the fork 18 is located between the two columns 21 and 22 of said frame. Between these two columns there is fixed and resting on the floor a cast base 25 presenting in its center a bearing 26 which receives the lower end of a vertical screw 27 whose upper end 10 passes through the bridge 24 and is held there by a plate bushing 27' which, at the same time, acts as its bearing and said screw has wedged at its other projecting end a gear 28 meshing with another gear 29 fixed 15 at the upper end of a vertical shaft 30 rotatively mounted in bearings 31 and 32 of which 31 is fixed at a side of the bridge 24 and 32 is laterally fixed to a plate 33 fixedly mounted between the columns 22 and 23, 20 the shaft 30 carrying at its lower end a beveled gear 34 which meshes with another beveled gear 35 fixed on a horizontal shaft 36 mounted on journals 37 fixed to columns 22 and 23 said shaft 36 carrying at its end a 25 hand lever 38 for the operation thereof.

The vertical screw 27 passes through a sliding nut 39 provided at its sides with horizontal trunnions 40 which pass through openings in bracket bearings 41 fitted within 30 the openings 20 of the fork branches 18 and slidably within said openings, the bearings 41 being held upon the trunnions 40 by means of collars 42 fixed to these by fore-lock keys 43 and trunnions 40 are extended 35 toward and near columns 21 and 22 and carry at their ends sleeves 44 terminating in bearings 45 which fit and slide within the inner channel formed by each column 21 or 22 whose channels serve as guides to those 40 bearings 45.

The operation of the device is as follows: Supposing that a loaded car 13 is placed upon the rails 12 of the platform and held thereto by means of appropriate chains 46, 45 the hand lever 38 is rotated in the proper manner whereby the horizontal shaft 36 moves, by means of the beveled gears 35 and 36, the vertical shaft 30 and, the gear 29 which in turn turns the other gear 28 and 50 with this the vertical screw 27, which being prevented from moving vertically, raises the nut 39 and the trunnions 40 which raise the branches of fork 18 by running along its openings 20 and with them the levers 15 are 55 raised, thus tilting the platform on the supporting base until reaching the inclined position shown in Fig. 4 in which, by virtue of its own weight, the load of car 13 is discharged therefrom. It will be noted that 60 the platform is never separated from the car supporting surface which is formed by the extension included between the two rails 12 whereby said platform is always held at a stable balance in any position thereof.

As it will be understood by the described 65 constructions in case of rupture of the whole moving mechanism or any part thereof, the platform would always remain in the same position which it had when the rupture occurred since it is impossible that the gravity force due to the weight of the car and of the platform gravitating on nut 39 may occasion the turning of screw 27.

It is obvious that the construction of the operating means of the spindle gear as well 75 as the structure of the platform can vary without altering the spirit of the invention which is as pointed out in the following claims.

What I claim is:—

1. In combination, a tilting platform for side dumping cars, a lever fixed at a side of the platform and terminating in a fork the branches of which have a longitudinal opening, a nut mounted between the two fork 85 branches and provided with trunnions passing through the openings of the fork branches, a screw passing across the nut and rotatively mounted on fixed supports, and means for rotating the screw. 90

2. In combination, a tilting platform for side dumping cars, a lever fixed at a side of the platform and terminated in a fork the branches of which have a longitudinal aperture, a nut disposed between the two 95 branches of the fork and provided with trunnions carrying blocks slidably mounted in the openings of the branches of the fork, a screw passing across the nut and rotatively mounted on fixed supports serving as a guide 100 for the ends of the nut trunnions, and means for rotating the screw.

3. In combination, a tilting platform for side dumping cars, a lever fixed at a side of the platform and terminating in a fork the 105 branches of which have a longitudinal aperture, a nut disposed between the two branches of the fork and provided with lateral opposite trunnions carrying bearings slidably mounted in the openings of the 110 branches of the fork, a screw passing vertically across the nut and rotatively mounted by its ends on a fixed frame, said frame presenting vertical channels which serve as a guide for bearings carried on the ends of 115 the nut trunnions, and hand lever actuated means for imparting a rotary movement to the screw.

4. A platform having a car track thereon, said platform being mounted for transverse 120 tilting movement and being provided at one side with a laterally extending lever, said lever having a pair of spaced members each provided with a longitudinal slot; bearings mounted for movement in said slots, a nut 125 arranged between the bearings and having trunnions extending through and projecting outwardly beyond the bearings, a vertical

frame having side members provided with guide channels, bearings arranged for vertical movement in said guide channels and in which the outer ends of the journals are 5 mounted, a vertical screw mounted in said frame and engaging said nuts, and means to operate said screw.

In testimony whereof I affix my signature in presence of two witnesses.

ANDRÉS PETIT.
